HANDLE FOR KITCHEN APPLIANCES

Vytant P. Aleks, Rockford, Ill., assignor to National Lock
Co., Rockford, Ill., a corporation of Delaware

Filed Aug. 29, 1966, Ser. No. 3,641

Term of patent 14 years

(Cl. D10—8)

FIG. 2 is a bottom plan view thereof;

FIG. 3 is a rear elevational view thereof;

FIG. 4 is an end elevational view thereof, and

FIG. 5 is a cross sectional view thereof taken on the line 5—5 of FIG. 2.

I claim:

The ornamental design for a handle for kitchen appliances, substantially as shown.
